UNITED STATES PATENT OFFICE.

CHARLES HUTCHINS, OF PATASKALA, OHIO.

MOLD FOR CEMENT POSTS.

No. 866,653.

Specification of Letters Patent.

Patented Sept. 24, 1907.

Application filed June 14, 1906. Serial No. 321,605.

To all whom it may concern:

Be it known that I, CHARLES HUTCHINS, a citizen of the United States, residing at Pataskala, in the county of Licking and State of Ohio, have invented certain 5 new and useful Improvements in Molds for Cement Posts, of which the following is a specification.

My invention relates to a mold for cement posts and the like and has for its object the provision of a device of this character adapted to receive and retain a body of 10 concrete or cement until the same hardens, said mold being constructed in such manner that it may be readily stripped from said post after the material has set.

A further object of the invention is the provision of a mold adapted to accomplish the objects set forth in the 15 foregoing paragraph and likewise to form a groove or recess in the face of the post.

A further object of the invention is the provision of a mold constructed in such manner as to receive and retain wire engaging members until the material forming 20 the post hardens or sets and also constructed in such manner that it may be readily stripped from the post and from said wire retaining devices after said material has hardened.

Further objects and advantages of the invention will 25 be set forth in the detailed description which now follows.

In the accompanying drawing: Figure 1 is a transverse vertical sectional view of a cement fence post mold constructed in accordance with the invention and 30 illustrating said mold surrounding a cement fence post, Fig. 2 is a horizontal section upon line $z-z$ of Fig. 1, Fig. 3 is a horizontal section of said cement fence post after the mold has been stripped therefrom and illustrating a strand of fence wire secured thereto, Fig. 4 is a view 35 similar to Fig. 3, illustrating a modified form of wire retaining member, Fig. 5 is a view partially in side elevation and partially in section of the post shown in Fig. 4 illustrating the mold inclosing said post, and, Fig. 6 is a view of the post itself, illustrating one of the retaining 40 devices bent about a strand of the fence wire.

Like numerals designate corresponding parts in all of the figures of the drawing.

Referring to the drawing and particularly to Figs. 1 and 2, the numeral 5 designates a tapering metallic casing 45 which forms the body portion of the mold. This casing is provided with flanges 6 which are perforated as at 7, for the reception of bolts 8. These bolts pass through a strip 9 which is preferably formed of wood and which has a V-shaped inner face 9'. The bolts 50 serve to clamp the flanges 6 firmly against the sides of the strip 9.

Wire retaining pins 10 which are headed as at 11 pass through perforations 12 formed in the strip 9 and serve a purpose which will be hereinafter set forth. A binding 55 wire or rod 13 passes vertically through the post and is

looped at its lower end 14. The upper end of this rod or wire extends to any desired distance above the top of the post and is adapted to have strands of the fence wire secured thereto.

The operation of the device is as follows: In using 60 this cement post mold, an excavation 15 is first formed in the ground, which is indicated by the numeral 16. This excavation is then partially filled with cement, after which the mold is placed in position with its lower end resting upon the body of cement which has 65 been placed in the excavation. The rod or wire 13 is then placed vertically in the mold and pushed down to the bottom of the cement previously placed in the excavation and said mold is filled with cement through its upper end. While this cement is still in a plastic 70 condition, the pins 10 may be moved through the openings 12 of the strip 9 to any desired position. After the cement hardens or sets, the bolts 8 are removed and the strip 9 is stripped from the pins. The V-shaped inner face of this strip leaves a V-shaped recess 75 17 in the face of the finished post (see Fig. 3). The body portion of the mold is then stripped from the post by slightly separating the flanges as illustrated in dotted lines in Fig. 2 and sliding the mold from the top of the post. It is apparent that the strip 9 may be 80 reversed to present its plane face to the post if it is not desired to form a groove therein. When the concrete hardens, the loop 14 is firmly embedded therein, as well as the wire 13 and the headed pins 10. The remainder of the excavation is then filled with earth. 85 That portion of the concrete which was placed in the excavation prior to placing the mold in position forms an anchor which resists any tendency of the post to move upwardly under the influence of frost. The strand wires of the fence, one of which is indicated at 90 18, are then run across the face of the post and the ends of the pins 10 are bent about said wires, as indicated at 19, drawing them into the V-shaped groove 17 to thereby secure any desired tension. These wires correspond in number to the pins 10 and these pins 95 may be spaced apart and of such number as to give a fence of any desired number of wires and of any desired height. A mold constructed as herein shown and described, renders it possible to mold the fence posts in the ground at the place where they are to be 100 used. By using a set of eight or ten of these molds, the operation of setting the posts may be steadily continued.

If desired, the heads 11 may be omitted from the pins and the pins passed entirely through the post and 105 through the opposite side of the mold, as is illustrated in Fig. 5. When this is done, the pins are pushed back just through the openings in the mold which are opposite the holes in the strip, which permits the mold being stripped from the post. Said pins are then 110

moved inwardly until their ends may be bent over upon the exterior of the post as is indicated at 20 in Fig. 4.

From the foregoing description, it will be seen that 5 simple and efficient means are herein provided for accomplishing the objects of the invention, but while the elements shown and described are well adapted to serve the purposes for which they are intended, it is to be understood that the invention is not limited to 10 the precise construction set forth, but includes within its purview such changes as may be made within the scope of the appended claims.

What I claim, is:

In a device of the character described, the combination 15 with a flexible and integral mold body which is open en-

tirely along one side thereof and which tapers toward its upper end, of an outturned flange formed upon the mold body at each side of its open portion, a strip having a series of centrally arranged perforations formed there-through which are adapted to receive fastening devices 20 that extend from the center of the post to be molded, said strip entirely filling the space between said flanges and being adapted to be stripped bodily from the fastening devices when moved away from the mold, and bolts removable from the exterior of the mold which pass through 25 both the flanges and the strip.

In testimony whereof I affix my signature in presence of two witnesses.

CHARLES HUTCHINS.
